United States Patent Office

Des. 204,386
Patented Apr. 12, 1966

204,386

CIRCUIT BREAKER

Ralph B. Davis and Ervin L. Kovacs, Trenton, N.J., assignors to Heinemann Electric Company, Trenton, N.J., a corporation of New Jersey

Filed Feb. 23, 1965, Ser. No. 83,915

Term of patent 14 years

(Cl. D26—13)

Fig. 5.

Fig. 7

FIG. 1 is a front elevational view of a circuit breaker, showing our new design;

FIG. 2 is a front, bottom and right side perspective view;

FIG. 3 is a fragmentary cross-sectional view partly in bottom plan, to an enlarged scale, taken on line 3—3 in FIG. 4;

FIG. 4 is a fragmentary front perspective view, to an enlarged scale;

FIG. 5 is a rear, top and left side perspective view

FIG. 5 is a rear, top and left side perspective view; FIG. 6 is a fragmentary side elevational view, partly cut away to show the configuration of the bottom cavity; and

FIG. 7 is a bottom plan view thereof.

The dominant features of our new design are shown in solid lines in the drawings.

We claim:

The ornamental design for a circuit breaker, as shown and described.
